GRENADE SIGHT FOR FIREARMS

Russell O. Persinger, Marion, Ohio

Application February 2, 1942, Serial No. 429,211

10 Claims. (Cl. 33—47)

(Granted under the act of March 3, 1883, as amended April 30, 1928; 370 O. G. 757)

The invention described herein may be manufactured and used by or for the Government for governmental purposes, without the payment to me of any royalty thereon.

This invention relates to removable sighting means for a firearm.

An object of this invention is to provide sighting means adapted to be placed upon a firearm to aid in the accurate launching of grenades.

Grenades are usually launched from the muzzle of a rifle at greater angles than those readable on the conventional rifle sights which, of course, are used when firing breech loaded projectiles. It is therefore an object of this invention to provide sighting means which allow a rifle to be accurately fired at greater angles of fire than may be obtained with the conventional type of sights on those rifles.

Another object of this invention is to provide sighting means on a rifle for large angles of fire and to dispose such sighting means on the rifle with no interference to the use of the conventional sights on the rifle.

Another object of this invention is to provide sighting means for accurately launching grenades from a rifle.

Another object of this invention is to provide grenade launching sighting means adapted to be placed on any one of different types of rifles.

The specific nature of the invention as well as other objects and advantages thereof will clearly appear from a description of a preferred embodiment as shown in the accompanying drawings in which:

Fig. 1 discloses a sighting means incorporating an embodiment of this invention and mounted on a firearm of the U. S. Army 1903 type.

Fig. 2 discloses a plan view of the assembly shown in Fig. 1.

Fig. 3 discloses a plan view of the sighting means shown in Fig. 1 but mounted on a firearm of the U. S. Army 1917 type.

Fig. 4 discloses a section substantially on line 4—4 of Fig. 1 but with the sighting bar 25 having zero elevation.

Fig. 5 discloses a section taken substantially on line 5—5 of Fig. 4.

Fig. 6 discloses the sighting means of Fig. 1 mounted on a rifle having a cross sectional portion as indicated in this figure, said rifle is of the type adopted by the U. S. Army to supersede the 1903 and 1917 models.

Fig. 7 discloses an end view of a modified sighting means of the type shown in Fig. 1.

Fig. 8 discloses another means for sighting a firearm at high angles.

Fig. 9 is a plan view of the sight 101 of Fig. 8.

Fig. 10 is a plan view of the sight 102 of Fig. 8.

Fig. 11 is an end view of sight 101 on the firearm of Fig. 8.

Fig. 12 is an end view of sight 102 on the firearm of Fig. 8.

The sighting means S disclosed in Figs. 1—7 are adapted to be centrally clamped on any one of three types of firearms; suitable faces are placed on the sighting means rendering that feature possible.

The sighting means S disclosed in Figs. 1—6 is assembled on the particular firearm by threading the front end of the firearm through the closed cross sectional portion shown in Fig. 4 until corresponding cooperating faces on the sighting means and firearm are adjacent; the sighting means S is then clamped to the firearm by means of clamping screw 10 which carries thumb screw 11 and also the self-aligning knurled clamping member 12 through the ball and socket connection 13.

In a firearm of the 1903 type (Fig. 2) the sighting means S is aligned on the firearm by means of the rectangular sight projection 14 on the firearm entering a corresponding cut-out portion 15 in the sighting means S.

In a firearm of the 1917 type the sighting means is aligned on the firearm by bringing face 16, Fig. 3, on the sighting means S into abutting relation with the oppositely disposed face 17 on collar 18 of the firearm with rounded portion 30 (Fig. 6) abutting a corresponding rounded portion (not shown) on the firearm, and with reference mark 19 (Fig. 6) on sighting means substantially in line with the center of the bore of the firearm.

In a firearm recently adopted by the U. S. Army and having a cross section as shown in Fig. 6, the sighting means S is aligned on that firearm by bringing faces 20, 21 on the sighting means S into close abutting relationship with corresponding faces 22, 23 respectively on the firearm.

With corresponding faces aligned in any one of the three arrangements described above, the sighting means S is clamped to that particular firearm by turning clamping screw 10.

The sighting bar 25 of the sighting means S is pivotally mounted on the cylindrical projection 26 (Figs. 1 and 4) of the ring-shaped cross sectional portion 27 and is clamped in relation thereto by means of thumb screw 28. The end of thumb screw 28 is peened over slightly at 29 so that it and the sighting bar 25 may not be-

come separated from the closed cross sectional portion 27. The movable sight bar 25 has mounted thereon the pair of aligned sighting members 25a, 25b; member 25a partakes of a peep sight but it is understood that sighting members 25a, 25b may take various forms and shapes as is well understood in the art. Sight bar 25 also includes the integrally formed plate or flange 25c (Fig. 4) having an arcuate slot 25d therein for the passage of thumb screw 28 which together with metallic washer 28a and resilient washer 28b serve to clamp plate or flange 25c to the ring-shaped cross sectional portion 27 in adjusted relationship. Graduations 25e on plate 25c are read using as a reference line zero line 27a on the extension 27b of ring-shaped portion 27. The particular graduations are in mils but it is understood the scale of the graduations may be different than those on the drawings.

In the modification shown in Fig. 7 provision is made whereby in assembling the sighting means S on the firearm no threading operation is required, as in the above arrangement. The ring-shaped cross sectional portion 27' is made with an opening 27a' through which the body of the firearm is adapted to pass. A straight round wire bent to form the perimeter of a rectangle 27b' serves as a closure member for the opening 27a'. One leg 27c' of the rectangular-shaped closure member is pivotally held in the turned over edge 27d' of portion 27'; the adjacent edge 27e' of portion 27' is also turned to serve as a hook for the other parallel leg of the rectangular-shaped closure member. In this modification the spring biased rod 10' serves the same function as the screw 10 above and in addition may serve to more securely hold closure member 27b' in its hooked position shown in Fig. 7 when the body of the firearm is disposed between the self-aligning clamping member 12 and cooperating faces on the ring-shaped portion 27'.

The sighting means S and the modification shown in Fig. 7 disclosed herein have been shown on a rifle but it is obvious that their use is not limited to application on rifles of one particular caliber but may be applied on machine guns or other firearms wherein it is desired to orient the path of a projectile which may not necessarily be a muzzle loaded projectile.

The sighting means disclosed herein may be varied from a depressed elevation setting to approximately a 45° elevation setting but it is obvious that by slight modification the slot 25d (Fig. 1) could be made longer or shorter whereby a larger or smaller range of elevations may be provided.

The physical size of the sighting means is such that it does not project within the line of sight of the normal sights carried on the firearm when accurately firing breech loaded projectiles and as a consequence the operator may alternately fire muzzle loaded grenades and breech loaded projectiles without changing the physical position of his sights. Also, it is obvious that for small angles of fire the sighting means S on the firearm may be used instead of the normal sights on the gun if conditions warrant such use.

In the arrangement disclosed in Figs. 8 to 12, two members 101, 102 each having a pair of sighting members thereon is mounted in spaced relationship along the longitudinal axis of a fire-

arm. held on the firearm by a corresponding flexible coil spring 103 which has one end fastened to a sighting member and adapted to partially encircle the firearm and have its other end hooked and insertable in a hole 104 in the sighting member.

Sighting members 101, 102 each have an auxiliary sight 101a, 102a, and a main sight 101b, 102b, respectively.

After the sighting members 101, 102 are mounted on the firearm by hooking the springs 103 in holes 104 in spaced relationship determined by the length of flexible link 107, the auxiliary sights 101a, 102a are aligned with the gun sights 105, 106 by sighting along the firearm. Sights 105, 106 are the normal sights furnished with the firearm. After auxiliary sights 101a, 102a are aligned, use is made of the main sights 101b, 102b to aim the firearm as the muzzle loaded firearm is discharged. Main sights 101b, 102b are of the fixed type but it is apparent that adjustable members may be mounted on one or each of the sighting members whereby the angle of fire of the aimed firearm may be varied.

Projections similar to those shown at 101p (Fig. 11) on member 101 may be provided to cooperate with cooperating grooves in the wooden stock or metallic portions of the firearm in order to more firmly secure the sights on the firearm.

A flexible metallic connecting link 107 serves as a gauge for the correct spacing of the sights 101a, 102a on the firearm and also prevents the two sights from becoming separated when disassembled from the firearm. Also, since the link 107 is preferably made flexible the disassembled sighting members require a minimum carrying space.

It is readily seen that the sights 101, 102 are readily adjustable on the firearm by virtue of the resilient springs 103.

I claim:

1. A pair of sighting members each having a pair of sights thereon, means for adjustably mounting the members on a firearm having aiming means, a link joining the members and serving to space the members a known distance apart, one of the sights of each member being adapted to be aligned with the firearm aiming means to accurately position the other sights relative to the axis of the firearm, and the other one of said sights on each member being adapted to be aligned with each other and with a target.

2. The same as in claim 1 and said link being flexible.

3. A sighting means for a firearm having an aiming means disposed on its upper surface with the center of the aiming means passing through the center of the firearm barrel comprising: a plate having a surface adapted to cooperate with the upper surface of the firearm, a sight on the plate and extending upward, a second sight depending downward from the plate and adapted to be disposed along the side of the firearm, and means adapted to adjustably align the first mentioned sight with the aiming means on the firearm.

4. A sighting member of substantially inverted L-shape, a sight on each leg of the inverted L-shaped member, and a resilient member joining opposite ends of one leg of the inverted L-shaped member to secure said member to the firearm.

5. A pair of sighting members each having a pair of sights thereon, means for adjustably mounting the members on a firearm having aim-

ing means, one of the sights of each member being adapted to be aligned with the firearm aiming means to accurately position the other sights relative to the axis of the firearm, and the other one of said sights on each member being adapted to be aligned with each other and with a target.

6. A pair of sighting members for a firearm having aiming means, an auxiliary sight on each member, a main sight on each member, means for mounting the auxiliary sights in alignment with the firearm aiming means, and means connecting the members and spacing them a known distance apart.

7. A substantially ring-shaped member adapted to have included therein a portion of a firearm, said member having at least one face adapted to cooperate with a corresponding face on one particular type of firearm, means carried by the ring-shaped member and engaging the firearm for clamping said faces together, a sight bar pivotally mounted on the ring-shaped member, and means for indicating angular displacements of the sighting bar.

8. The same as in claim 7 and said substantially ring-shaped member has a cut-out portion defining an opening for radial passage of the firearm through the ring-shaped member.

9. A substantially ring-shaped member adapted to have included therein a portion of a firearm, said member having a cut-out portion defining an opening for radial passage of the firearm through the ring-shaped member, a closure member for said opening hinged on the ring-shaped member, a spring biased self-aligning clamp carried on the lower portion of the ring-shaped member and engaging the firearm for clamping the same when in the ring-shaped member, a sighting bar pivotally mounted on the ring-shaped member, and means for indicating angular displacements of the sighting bar.

10. A substantially ring-shaped member adapted to have included therein a portion of a firearm, means carried by the ring-shaped member for clamping the ring-shaped member to the firearm, a projection on the ring-shaped member, a sight bar having a flange extending substantially perpendicular to the line of sight of the sight bar, said projection comprising means for pivotally mounting the sight bar, said flange having an arcuate slot therein, a clamping screw passing through the arcuate slot and retained by the ring-shaped member, and means for indicating the angular displacement of the sight bar.

RUSSELL O. PERSINGER.
